COMBINATION BAG AND BOOK COVER

Philip A. Spaldo, New York, N. Y.

Substituted for abandoned application Serial No.
336,533, May 22, 1940. This application July 11,
1944, Serial No. 544,388

1 Claim. (Cl. 281—34)

This invention relates to combination ladies' bags or purses and book covers, and aims to provide such a combination article having an adjustable book cover provided integral and forming part of the bag. By providing the combination of bag and book cover, a book may be readily carried about together with the bag in a convenient and readily accessible manner, instead of having to carry two separate articles, which is not only troublesome but often results in the loss or dropping of one of them.

Another object of the invention is the provision of the book cover, forming part of the combination, with extensible means so that the same may be accommodated to any size book within ordinary limits, and the cover will snugly fit any size of book within such limits. Thus, the book will not only be held firmly within the cover, but the combination containing the book will at all times present an attractive and neat appearance.

A further object of the invention is the provision of an adjustable or extensible strap adapted to releasably close and open ends of the book cover at all times, whether or not a book is contained within the cover. This strap is also extensible to accommodate any thickness of book within the usual limits, and securely holds the two open ends of the cover together, also thereby offering a neat, compact and attractive whole.

The above and other objects will become apparent in the description below, reference being had to the accompanying drawing which is presented for the purpose of illustration only and is not to be construed as a necessary limitation to the specific details shown, as the underlying features of the invention may naturally be carried out in a number of ways, of which the one herein presented is but one example.

Referring briefly to the drawing,

Figure 1 is a perspective view of the article in closed position, showing a relatively narrow book contained therein.

Figure 2 is a similar but fragmentary view, showing a relatively wider book contained therein.

Figure 3 is a plan view of the inside of the book cover in extended position.

Figure 4 is a similar view, partly in section, of the reverse side of the article.

Figure 5 is a cross-sectional view taken on the line 5—5 of Figure 1.

Figure 6 is a cross-sectional view taken on the line 6—6 of Figure 4.

Referring in detail to the drawing, the numeral 10 indicates a hand bag having the front wall 11 and an inner wall 12, the flap or closure 13 ex-

tending from the inner wall 12. Between the walls 11 and 12 is the compartment of the bag 10. A rear wall 14, secured along its bottom and side edges to the same edges of the front wall 11, or even formed integral therewith along the said edges, provides a space or compartment 15, open at the top, between itself and the inner bag wall 12. A pocket 16 is formed on the exterior surface of the rear wall 14 at the lower end thereof, by securing thereto along its bottom and side edges a flap 17, this pocket being open at the top as shown in Figure 5.

The parts thus far described may be considered one section of the article. The other section comprises a pair of walls 18 and 19, of substantially the same dimensions as the wall 14, joined along their bottom and side edges and open at the top, providing a compartment 20 therebetween. A pocket 21, similar to and complementary with the pocket 16, is formed on the exterior surface of the wall 19 by securing thereto along its bottom and side edges a flap 22.

An intermediate book cover member 23 has one end 24 secured to the wall 12 along its lower edge, 25 within the compartment 15. The other end of the member 23 enters into the compartment 20 and is 30 slidable therein; this end is shown at 25. A pair of spaced, parallel elastic strips, made of any desired elastic material, 26, are secured to one side 35 of the member 23, and the extremities of these strips, which extend beyond the end 25 of the member 23, are secured to the bottom edge of the compartment 20, as shown in Figure 5. Thus, through the medium of the lengths of these elastic strips between the bottom edge of the end 25 of the member 23 and the extremities of the strips, which are anchored as just-mentioned, the member 23 may be pulled outward from the compartment 20 and, upon being released, will be pulled 40 back by these elastic strip extensions.

A strap 27 has a similar elastic strip 28 secured to the inner end thereof against the inner surface of the rear wall 18, the strip 28 being anchored at 29. Thus, the strap 27 may also be yieldably 45 pulled out.

It is to be noted that the inner exposed surfaces of the various parts described may be covered with cloth lining.

The walls 12, 14, and 19, as well as the flaps 17 and 22, may be formed entirely of cloth, whereas the other parts are mostly leather, covered, if desired, with a cloth lining. This construction is provided only for illustration of the most presentable and inexpensive method of construction, but 55 forms no part of the invention.

In using the article as a book cover, the ends of the book covers themselves are inserted into the pockets 16 and 21, with the member 23 covering the book binding. When the book is a relatively thick or wide one, it is obvious that the member 23 will adapt itself to whatever the thickness is, through the yieldable elastic strips 26. Likewise, the strap 27 will adapt itself through its yieldable elastic strip 28; a snap button 31 engages a snap 32 to lock the strap in closed position.

Thus an adjustable book cover has been provided in combination with a purse or hand bag, which is simple in operation and adaptability to books of various sizes, inexpensive in cost of construction, and neat and attractive in appearance.

Obviously, modifications in form and structure

may be made without departing from the spirit and scope of the invention.

This application is a substitute for abandoned application, Ser. No. 336,533 filed May 22, 1940.

5 I claim:

In an article of the class described, a pair of opposed complementary sections having an intermediate substantially inelastic yet flexible member such as leather, said member being rigidly secured to one of said sections at one end, the other end of said member having elastic strips extending therefrom, said strips being anchored in said other section, said sections being adapted to enclose a book with said member covering the binding of the book.

PHILIP A. SPALDO.
